UNITED STATES PATENT OFFICE.

MORRIS SAPO, OF NEW YORK, N. Y.

CUFF-LINK.

1,219,873.

Specification of Letters Patent. Patented Mar. 20, 1917.

Application filed August 5, 1916. Serial No. 113,253.

To all whom it may concern:

Be it known that I, MORRIS SAPO, a citizen of the United States, and a resident of the city of New York, borough of Manhattan, in the county and State of New York, have invented a new and Improved Cuff-Link, of which the following is a full, clear, and exact description.

My invention relates to cuff links. The object thereof is to provide a simple and inexpensive self-locking link which will not unlock accidentally.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a perspective view of my link; Fig. 2 is a longitudinal section through the link;

Fig. 3 is a similar section showing the slide displaced; and

Fig. 4 is a cross section on line 4—4, Fig. 2.

Referring to the drawings, 5 is a link shaped from a suitable bar. It has a central bridge 6 uniting the sides which reinforce the link. The link has a pair of gaps 7 in the side thereof, the gaps being on the opposite sides of the bridge 6 and, therefore, forming entrance to the opposite ends of the link. A spring housing 8 is mounted to slide on the link 5. The end walls 9 of the housing are restored to their normal position after the housing has been placed on to the link and the springs 10 inserted into the housing. The length of the housing is such that normally it will cover the two gaps 7 of the ring. The two springs 10 being of the same strength balance each

other and maintain the gaps 7 normally closed. To clear either of the gaps, the housing must be forced to one or the other end, as shown in Fig. 3. The compressed spring 10 will restore the housing to its normal position after the housing is released. It will be noted that the bridge 6, in addition to forming a reinforcement for the link, forms an abutment for the springs 10.

Generally the cuff buttons being considerably larger than the width and thickness of the housing 8, there is small possibility that any obstruction may come into engagement with the housing because of the displacement thereof on the link. But even if such a tendency should arise, the eyes of the buttons extend sufficiently into the link to bar a material displacement of the housing on the link, thus insuring that the housing will not be displaced accidentally on the link to expose a gap.

I claim:

1. A cuff link comprising in combination a link having a central bridge, said link having a pair of gaps in the sides disposed on the opposite sides of the bridge and adjacent thereto, a spring housing slidably mounted on the link and having a length exceeding the distance between the remote ends of the gaps, and a pair of springs in said housing on the opposite side of the bridge and in engagement therewith.

2. A cuff link comprising in combination a link having a central bridge, said link having a pair of gaps in the same side, each gap being on the opposite side of the bridge, a spring housing slidably mounted on the link and having a length exceeding the distance between the remote ends of the gaps, and a pair of springs in said housing on the opposite side of the bridge in engagement therewith for maintaining said housing over the gap.

MORRIS SAPO.
